FIG. 2.

INVENTOR:
WILMOT H. SCOTT,

BY Harry Barnes
ATTORNEY.

UNITED STATES PATENT OFFICE

127,925

DESIGN FOR A BENCH

Wilmet H. Scott, St. Louis, Mo.

Application September 9, 1940, Serial No. 94,903

Term of patent 7 years

To all whom it may concern:

Be it known that I, Wilmet H. Scott, a citizen of the United States, residing in St. Louis, State of Missouri, have invented a new, original, and ornamental Design for a Bench, of which the following is a specification, reference being had to the accompanying drawing, forming a part thereof.

showing my new design; and Figure 2 is a front elevational view thereof.

The side of the bench opposite to that shown is in all substantial respects similar to that shown.

I claim:

The ornamental design for a bench, as shown and described.

WILMET H. SCOTT.
